DISPLAY SUPPORT FOR CONTAINERS

Andrew Chappory, Brooklyn, N. Y., assignor to
National Biscuit Company, New York, N. Y., a
corporation of New Jersey

Application June 6, 1941, Serial No. 396,806

5 Claims. (Cl. 248—311)

My invention relates to a display support for containers and in the form which I have selected for illustration is particularly adapted to support a caddy or "Q" of biscuit or other bakery products on a shelf, counter or table at such an angle as to effectually display the contents. The support requires a minimum of room or space, and utilizes space that otherwise is wasted.

In grocery stores, markets, delicatessens and the like, space for displaying the many kinds of merchandise is at a premium and all sources of supply are vying with one another to get the best or most effective display space for their products. This has resulted in the introduction of many kinds of display racks, cabinets and other fixtures, but all of them have this objection that they utilize space that is needed for other purposes or articles. By means of the present invention, I am able to use the edge of a counter, table or shelf, that otherwise would be unused, to support a caddy of merchandise in position where its display will be most effective. In another form of the invention, the caddy may be supported on any flat surface, as the top of a table or counter, at the height where the merchandise can be best seen by the prospective customer and where it will occupy a minimum of space.

Referring now to the drawings,

Fig. 1 is a front elevation showing a caddy supported on the front of one of a tier of shelves that are filled with other merchandise.

Fig. 2 is a side elevation of Fig. 1.

Fig. 3 is an enlarged section through the support and part of a carton.

Fig. 4 is a view along the line 4—4 of Fig. 2.

Fig. 5 is a perspective view of the invention adapted for use on a flat supporting surface.

Fig. 6 is a cross-section of Fig. 5, showing a caddy on the support.

Fig. 7 is a view, partly broken away, along the line 7—7 of Fig. 6.

In Figs. 1 to 4, I have shown my invention adapted to support a caddy of biscuit in display position on the front edge of one of a tier of shelves 10 on which various articles of merchandise 11 are stacked. The caddy 12 is made from heavy moisture-proof cardboard and on its front or top face carries the usual glass-front display cover 13. The bottom of the caddy as shown in Fig. 4 has opposite closing flaps 14, 15, the length of which is equal to one dimension of the caddy and the width of which is a little greater than half of the other dimension of the caddy so that the flaps overlap at the center. Sealing flaps 16,

17 are relatively narrow and are secured by staples 18 to the closing flaps adjacent their side edges to close the bottom.

The support comprises a sheet metal plate 19 having its lower edge bent forward to form a ledge or rest 20, the upper face of which lies in a plane at right angles to the face of the plate, and having its upper edge cut away to provide a tongue 21 which is slightly less in width than the distance between the inner edges of the sealing flaps 16, 17. This plate is secured to a bracket or clamp 22 in any suitable manner as by rivets 23 or spot-welding and the bracket has an upper horizontal arm 24 and a lower arm 25, the lower arm carrying a clamping screw 26 and the upper arm having a pad or buffer 27 made from rubber or other suitable material so that it will not scratch the upper surface of the shelf 10 or table or counter to which the clamp may be fastened.

In using the invention, the support is secured to the front edge of a shelf, table, counter, or the like by the clamping screw 26 and then the caddy with the display cover 13 in place is placed with its bottom against the plate and slid down until the front or bottom edge of the caddy comes to rest on the ledge 20 and the tongue 21 slips under the edge of the outer sealing flap 14. In some cases the overlapping edges of the flaps 14, 15 may be secured together at the center by a staple 28, as indicated in dotted lines in Fig. 4. If such a staple is used, it will be removed before the caddy is placed on the support.

It will thus be seen that I have provided a means for supporting a caddy of biscuit or other merchandise in excellent display position and without utilizing any space in the store that would be used for other merchandise. When the caddy is mounted on a shelf as indicated in Figs. 1 and 2, no space on the shelf is taken up but the shelves can still be used for stacking the merchandise just as though the support were not there.

In Figs. 5 to 7, I have shown another form of my invention which may be used for supporting a caddy on top of a counter, table or the like. In this form of the invention the metal plate 29 is supported on a frame made from a rod or heavy wire, the two ends of the rod 30, 31 being welded, brazed or otherwise secured to the back of the plate. From the plate the wire is bent down and then forward to provide a horizontal base 32, 33 which is adapted to rest on the table or counter. Intermediate the ends of the parts of the wire that provide the base, they are bent upwardly and forward to provide loops 34, 35 which ex-

tend at right angles to the plate 29 and form a rest similar to the ledge or rest 20 on which the lower forward edge of the caddy rests.

The plate 29 has a tongue 36 at its upper edge which may be offset from the plane of the plate as shown in Fig. 5 or may project from the upper edge the same as the tongue 21 in Figs. 3 and 4.

When the tongue 21 or 36, lies in the same plane as the plate 19 or 29, it will press outward on the closing flap 16 and the plate will press inward on the sealing flaps 16, 17 with a clamping or binding effect to hold the carton firmly in display position.

In using this form of the invention, the support is placed in the desired place on the counter and after affixing the display cover 13, the bottom of the caddy is placed against the plate 29 and slid down until its front edge bears on the rest 34, 35 and the tongue 36 slides under the bottom closing flap 14 as clearly shown in Figs. 6 and 7.

While I have shown the plate 29 as a short plate in Fig. 5, it may be replaced by the plate shown in Figs. 3 and 4 in which case the ledge 20 will take the place of the loops 34, 35 and these loops will be omitted.

While I have shown the supporting plates 19 and 20 as adapted to hold only a single caddy, they may of course, be made of sufficient length to support two or more caddies.

The form of the invention shown in Figs. 5 to 7 effectually displays the merchandise in the caddy and it may be placed any place in the store where a very small space is available and does not take up any appreciable amount of room as do the usual display racks.

The tongue 21, or 36, may be substantially as wide as the space between the flaps 16, 17 as shown in Figs. 4 and 7, or it may be cut away at the center so as to be formed in two parts. When the tongue is divided thus, the two parts will straddle a staple such as the staple 28, if it be used, and it need not be removed before placing the caddy on the support.

Having thus described my invention, what I claim and desire to secure by Letters Patent is:

1. A support for a container of the kind having bottom closing flaps which overlap at their inner edges comprising a metal plate having a tongue at its upper edge of less width than the plate, a rest below the tongue and lying in a plane perpendicular to the plane of the tongue, and means for supporting the plate in inclined position with the bottom of the container resting against one face of the plate, the tongue extending under the outer bottom closing flap and one side bearing on said rest.

2. A support for a container of the kind having bottom closing flaps which overlap at their inner edges and bottom sealing flaps overlapping

and secured to opposite side edges of the closing flaps comprising a metal plate having a tongue at its upper edge of less width than the plate, a rest below the tongue and lying in a plane perpendicular to the plane of the tongue, and means for supporting the plate in inclined position with the tongue extending under the outer closing flap between the sealing flaps, the sealing flaps resting against the plate and one side bearing on said rest.

3. A support for a container of the kind having bottom closing flaps which overlap at their inner edges and bottom sealing flaps overlapping and secured to opposite side edges of the closing flaps comprising a metal plate having a tongue at one edge of less width than the plate, a laterally extending ledge at the opposite edge perpendicular to the plate, and means for supporting the plate in inclined position with the tongue at the top and the ledge extending forwardly from the lower edge, whereby the container may be supported with one side resting on the ledge and the tongue engaging under the outer closing flap with the sealing flaps bearing on the plate.

4. A support for a container of the kind having bottom closing flaps which overlap at their inner edges and bottom sealing flaps overlapping and secured to opposite side edges of the closing flaps comprising a metal plate having a tongue on one side of less width and of less height than the plate, a ledge extending from the opposite edge at right angles to the face of the plate and tongue, and a bracket secured to the face of the plate opposite the ledge and adapted to be fastened to the edge of a shelf for supporting the plate in inclined position with the tongue at the top extending rearwardly over the shelf and the ledge extending forwardly from the lower edge, whereby the container may be supported with one side resting on the ledge and the tongue engaging under the outer closing flap with the sealing flaps bearing on the plate.

5. A support for a container of the kind having bottom closing flaps which overlap at their inner edges and bottom sealing flaps overlapping and secured to opposite side edges of the closing flaps comprising a metal plate having a tongue on one side of less width than the plate, a frame secured to said plate and having a base adapted to rest on a horizontal surface and support the plate in inclined position with the tongue at the top, said frame having rests extending forward substantially perpendicular to said plate, whereby the container may be supported with one side against said rests and the tongue engaging under the outer closing flap with the sealing flaps bearing on the plate.

ANDREW CHAPPORY.
